CLAIM

The ornamental design for a closeable container, as shown and described.

DESCRIPTION

FIG. 1 is a perspective view of a first embodiment of the closeable container; showing our new design;

FIG. 2 is a left side elevation view thereof, the right side being a mirror image;

FIG. 3 is a front elevation view thereof, the rear being a mirror image;

FIG. 4 is a top plan view thereof;

FIG. 5 is a bottom plan view thereof;

FIG. 6 is another perspective view thereof, showing the closeable container in an open configuration;

FIG. 7 is a perspective view of a second embodiment of the closeable container; showing our new design;

FIG. 8 is a left side elevation view thereof, the right side being a mirror image;

FIG. 9 is a front elevation view thereof, the rear being a mirror image;

FIG. 10 is a top plan view thereof;

FIG. 11 is a bottom plan view thereof; and,

FIG. 12 is another perspective view thereof, showing the closeable container in an open configuration.

In the Figures, the dash-dash broken lines are for the purpose of illustrating perforations.
